UNITED STATES PATENT OFFICE.

PAUL VELARDO, OF SOMERVILLE, AND JOHN VELARDO, OF BOSTON, MASSACHUSETTS.

HAT-PROTECTOR.

1,106,527.

Specification of Letters Patent. Patented Aug. 11, 1914.

Application filed November 10, 1913. Serial No. 800,092.

To all whom it may concern:

Be it known that we, PAUL VELARDO and JOHN VELARDO, citizens of the United States of America, residing at Somerville and Boston, respectively, in the counties of Middlesex and Suffolk, respectively, and State of Massachusetts, have invented certain new and useful Improvements in Hat-Protectors, of which the following is a specification.

10 This invention relates to hat protectors and has for its object the provision of an improved device of this character constructed in such manner that it may be very quickly and easily applied to the hat it is desired to protect and one that may be very economically manufactured.

15 It is a further object of the invention to provide in a commercial article of this nature, such a structure that the hat protector will readily adapt itself to hats of a wide range of sizes so that the necessity for providing a large number of sizes of the hat protectors will be avoided.

20 Further objects and advantages of the invention will be set forth in the detailed description which now follows:

25 In the accompanying drawing, Figure 1 is a sectional view of a hat having a protector embodying the invention applied thereto, and Fig. 2 is a side view of the protector removed from the hat.

Like numerals designate corresponding parts in both of the figures of the drawing.

Referring to the drawing, 5 designates the 30 crown and 6 the brim of a straw hat of ordinary construction. The protector is made of thin rubber of the kind commonly known as "dam rubber" and when in use, completely covers the outer sides of the crown and brim as shown in Fig. 1. The weather-proof covering thus formed comprises a top member 7, side walls 8, and a brim embracing portion 9. At the terminal edge of the brim embracing portion, a pocket 10 is formed by 35 folding the material upon itself and in this pocket a longitudinally elastic cord 12 is located. This cord may be endless though preferably its ends are tied together to render it longitudinally adjustable for the purpose hereinafter set forth. A separate strip 40 of material indicated at 13 is secured at the juncture of side walls 8 and brim embracing portion 9, and forms a pocket in which a lon-

gitudinally elastic cord 14 has a seating. This cord like cord 12 may be endless though 45 preferably its ends are tied together to render it longitudinally adjustable.

A hat protector constructed as herein shown and described will snugly and neatly fit hats of varying sizes.

We are aware of the fact that it has heretofore been proposed to provide hat protectors of elastic material having longitudinally elastic, enlarged portions at their edges and at the juncture of the brim and 55 crown of the hat. We are also aware of the fact that it has heretofore been proposed to provide a non-elastic draw cord in a pocket formed in the brim engaging edge of the protector. Our invention goes materially 60 farther than this, however, in providing separate, longitudinally elastic cords at both of these points by virtue of which structure, special machinery is not necessary in the manufacture and the devices may be more 65 cheaply and more readily made. In addition to this, a wide range of adjustment to fit hats of varying sizes and different widths of brim is provided.

From the foregoing description, it will be 70 seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within 75 the scope of the appended claims.

Having described our invention, what we claim is:

1. A hat protector formed of a thin, highly elastic material of such amplitude as to embrace both the crown and the brim of a 85 hat, a longitudinally extending, continuous pocket formed at the juncture of the crown embracing portion with the brim embracing portion, a continuous longitudinally extending pocket formed at the edge of the brim 100 embracing portion, and longitudinally elastic cords seated in said pockets.

2. A hat protector formed of a thin, highly elastic material of such amplitude as to embrace both the crown and the brim of 105 a hat, a longitudinally extending, continu-

ous pocket formed at the juncture of the crown embracing portion with the brim embracing portion, a continuous longitudinally extending pocket formed at the edge of the 5 brim embracing portion, longitudinally elastic cords seated in said pockets, and means for adjusting the length of said longitudinally elastic cords.

In testimony whereof we affix our signatures in presence of two witnesses.

PAUL VELARDO.
JOHN VELARDO.
